UNITED STATES PATENT OFFICE.

JOHN L. WHEELER, OF ST. LOUIS, MISSOURI, ASSIGNOR, BY DIRECT AND MESNE ASSIGNMENTS, TO SIMPLEX SHOE MACHINERY COMPANY, OF ST. LOUIS, MISSOURI, A CORPORATION OF MISSOURI.

WORK-PIERCING DEVICE FOR SEWING LEATHER AND THE LIKE.

1,184,059.

Specification of Letters Patent.

Patented May 23, 1916.

Application filed December 4, 1913. Serial No. 804,592.

To all whom it may concern:

Be it known that I, JOHN L. WHEELER, a citizen of the United States, residing in the city of St. Louis and State of Missouri, have invented new and useful Improvements in Work-Piercing Devices for Sewing Leather and the like, of which the following is a specification.

This invention relates to the sewing of leather and similar heavy material, and more particularly to the stitching of soles to the welts or uppers of shoes.

It has for its principal objects to provide, in a similar manner, a channel or groove in the surface of the material in which the stitching thread is laid or embedded between the respective punctures; to produce an improved puncturing or piercing device so as to obviate the necessity for employing a separate channeling or grooving device; and to attain certain other advantages which will hereinafter more fully appear.

The invention consists essentially in providing an awl or a needle or thread-carrying puncturing element with a major channeling portion on one side and a correlated minor channeling portion on the opposite side, said portions being arranged and adapted to cut or indent the material between the punctures therein so as to produce, in effect, a continuous channel or groove.

The invention further consists in the parts and in the arrangements and combinations of parts hereinafter described and claimed.

In the accompanying drawings,—Figure 1 is a fragmentary view showing, in section, two layers of material representing, respectively, a shoe sole and a welt punctured by an awl made according to the invention; Fig. 2 is a section through the two layers of work along the line of stitching, illustrating a loop-lock-stitch, and the manner in which the awl produces the channel or groove for depressing or embedding the locking thread; Fig. 3 is a fragmentary inverted plan view showing the arrangement of the punctures with the interposed alined grooves; Fig. 4 is a section similar to that shown in Fig. 1, but with the awl removed so as to show the contour of the puncture and channel; Figs. 5 and 6 are views illustrating a modification of the awl adapted for a plain straight puncture; Figs. 7 and 8 are, respectively, an inverted plan view and a section showing the kind of puncture and channel made by the awl illustrated in Figs. 5 and 6; Fig. 9 is a view illustrating a further modification of the awl wherein the channel-forming portion is blunt or rounded so as to indent instead of cutting the material to form the channel; Figs. 10 and 11 are, respectively, views of a hooked needle and an eye needle provided with channel-forming portions according to the present invention; Figs. 12 and 13 are views illustrating a further modification wherein the awl or the needle is detachably mounted in a divided or separable holder which is provided with a channeling portion; and Fig. 14 is a section on the line 14—14 of Fig. 13.

Referring now more particularly to Figs. 1 to 4, inclusive, two layers of work are shown, representing, respectively, a shoe sole 1 and a welt 2 to which the sole is stitched. The two layers are shown as stitched together by a loop-lock-stitch comprising a stitching thread proper 3, and a locking loop thread 4, the stitching thread 80 being looped through the work from the welt side and the locking thread being carried along the bottom of the sole and looped through the loops of the stitching thread. The interlooped threads 3 and 4 are drawn up into flared or tapered enlargements 5 of the punctures 6 which are formed by a tapered enlargement 7 of the awl 8, while the thread between the punctures is drawn into the grooves or channels 10 formed between the punctures by the channeling portions 9 on the awl.

The channeling portions 9 on the awl may be formed wedge-shaped with a relatively sharp cutting edge, as shown in Figs. 1 and 2, so as to cut into the material, or they may be made blunt or rounded, as shown in Figs. 9 and 11, so as to indent the material in forming the channel or groove. These channeling portions 9 are preferably provided on both sides of the awl, as shown, the major portion on the one side extending farther than the minor portion on the opposite side so that as the awl forms the successive punctures through the work a channel is cut in the surface thereof ahead of each puncture by said major channeling portion of the awl while the minor portion

overlaps the preceding channeling cut or indentation just sufficiently to insure the continuity of the channel without cutting or damaging the thread of the preceding 5 stitch.

In the construction and arrangement of a work piercing and channeling device according to the present invention, the major channeling portion may be made to extend 10 any desired distance from the side of the puncturing stem so as to provide for a given maximum length of stitch or distance between punctures, and it is only necessary to have the minor channeling portion extend 15 slightly from the side of the puncturing stem so as to overlap the preceding channeling cut or indentation in the region of the puncture sufficiently to prevent obliteration of that portion of the channel, as would 20 happen owing to the displacing and crowding of the material in the region of the puncturing stem during the puncturing operation. This relative arrangement of puncturing and channeling portions is also 25 advantageous in traveling a circular or other curved line, as for example, in rounding the toe portion of a shoe sole, particularly a rather sharp pointed toe. In such cases the minor channeling portion maintains the 30 continuity of the channel without appreciably cross-cutting the channeling cut made by the major channeling portion during the preceding operation. Hence, a neater finish is 35 obtained than if the channeling portions were extended a considerable distance on both sides of the puncturing stem.

In cases where it is not desirable to enlarge the punctures to receive the inter-looped threads, the awl may be made 40 straight so as to form the punctures and groove as shown in Figs. 5 to 8, inclusive.

In the modification illustrated in Figs. 12 to 14, inclusive, the awl is detachably mounted in a divided or separable holder. 45 That is, the holder comprises two separable sections 11, 11^a, which are inserted through a clamping member 12 provided with a set

screw 13, said set screw being adapted to clamp the portions 11 and 11^a upon the awl. In this modification the channeling portions 50 9 are provided on said awl-holder sections.

In some cases, instead of providing the awl with the channeling portions the needle or thread-carrying element may be provided with these portions, as shown in Figs. 10 55 and 11, the former illustrating a hook needle and the other an eye needle. So, too, in some cases both the awl and the needle may be equipped with channeling portions, especially where the awl and needle enter the 60 work from opposite sides. In this way both sides of the work may be channeled.

Obviously, the invention is adapted for either straight or curved awls or needles, and may be used for either machine or hand 65 work; and the construction and arrangement admits of considerable modification without departing from the spirit of the invention.

I claim:

Means for puncturing and channeling leather and the like for the sewing thereof, the same comprising a puncturing stem, and coöperating members on opposite sides of 70 said puncturing stem for forming a channel in the surface of the work connectedly with a series of punctures pierced successively by said stem, one of said channeling members being relatively elongated to constitute the major channel former and operating in advance of the respective punctures, and the other member being relatively short but arranged and adapted to overlap the preceding channel formed by said major portion 75 so as to preserve the continuity of the chan- 80 nel.

In testimony whereof, I have hereunto set my hand in presence of two subscribing witnesses.

JOHN L. WHEELER.
